SPARK PLUG

Elmer P. Hansen, Lincoln, Nebr., assignor of one-eighth to Clarence L. Mattson and one-eighth to C. Russell Mattson, both of Lincoln, Nebr.

Application November 30, 1934, Serial No. 755,385

2 Claims. (Cl. 123—169)

My invention relates to spark plugs of the kind especially designed for use in high compression cylinders.

One of my objects is the provision of a spark plug having a spark gap within the socket of the shell and at the point of greatest efficiency within the socket.

Another of my objects is the provision of a spark plug having a spark gap positioned appreciably within the socket and so arranged that the electrodes may be readily adjusted for increasing or decreasing the space between the electrodes.

Another of my objects is the provision of a ground electrode which is declined from a special combustion ring fitted high in the base.

A very important object in my invention is the provision of a ground electrode which is anchored to the special combustion ring within the spark plug by the distortion of the metal of the ring and of the electrode.

Having in view these objects and others which will be pointed out in the following description, I now refer to the drawing in which

Figure 1 is a view partly in elevation of the entire spark plug and partly in section of the shell, the washers, gasket, and combustion ring, the figure being drawn to an enlarged scale.

Figure 2 is a view showing the combustion ring with the ground electrode attached in section, showing a modification of my invention, the view being drawn to show the position of the electrodes in case of hot motors.

Figure 3 is a view showing the combustion ring with the ground electrode attached in section, showing a modification of my invention, the view being drawn to show the position of the electrodes in case of medium cool motors.

Figure 4 is a view showing the combustion ring with the ground electrode attached in section showing a modification of my invention, the view being drawn to show the position of the electrodes in case of a cold motor.

Figure 5 is a view showing the combustion ring with the ground electrode attached in elevation to more clearly disclose the anchor of the ground electrode.

The spark plug as shown includes a shell 10, a core 11, of stone or porcelain or other dielectric, a bushing 12, and a gasket 13, the core 11 having a rib 11'.

The central electrode 15 passes through the core 11 and terminates at its upper extremity in a screw threaded portion for receiving the nut 19. As thus far described the structure is well

known, being common to spark plugs of many types. As is usual in spark plugs, the gasket is made of a relatively soft material having high thermo-conductivity. The gasket should be sufficiently soft to yield slightly under compression in order to provide an effective seal. Since one of its chief functions is to conduct the excess heat to the shell 10 and to thus dissipate the heat, it must be made of an effective heat conducting material.

The core 11 is provided with lower and upper annular shoulders for seating the gaskets 13 and 14 in a manner such that both gaskets will be compressed when the bushing 12 is forced down into the shell 10. It should also be noted that the parts are so proportioned that an elongated annular air space will be formed between the shell 10 and the core 11 as shown in Figure 1. This annular air space functions to assist in the dissipation of the excess heat through the shell 10.

My spark plug includes a detachable ring 16 for supporting the ground electrode 17. This ring is flared outwardly to provide a flange which rests on an inner shoulder of the shell 10 as shown in Figure 1. The ring is of a size such that it nowhere contacts with the core 11 which it surrounds. This is due not only to its larger diameter than that of the core but also to the inner bevel in the upper portion of the ring 16 as clearly shown in Figure 5. This construction has for its purpose the provision of an unobstructed passageway for the hot gases of combustion, the passageway extending from the gasket 13 to the mouth of the spark plug. This passageway is of importance in dissipating the excess heat and in thus lowering the temperature of the spark plug, this being of prime importance in spark plugs which are to be used in high compression motors.

In the present instance instead of the electrode 15 extending to within close proximity of the mouth of the shell 10, the electrode is shortened to bring the extremity into a position of maximum efficiency of the spark gap in high combustion cylinders.

The ground electrode 17 then approaches the electrode 15 from the combustion ring 16 near the center of the shell 10, passing first in a declined position towards the center of the spark plug and away from the combustion ring, the direction then being changed abruptly so as to approach the electrode 15 at an angle more nearly approaching right angles.

In anchoring electrode 17 in the combustion

ring 16, I first drill an aperture through the center of the base of the combustion ring. This aperture is of a diameter to snugly receive the electrode 17.

- 5 When the electrode has been inserted in the aperture thus formed, a center punch is applied at the point 18 and is given a sharp blow which distorts the metal of the combustion ring 16 and of the electrode 17, which will hold the electrode 10 in place regardless of the heat fluctuation in the spark plug. Neither the concussions of the explosion nor the ordinary mechanical blow can 15 loosen the electrode which is thus anchored in the shell.
- 15 The construction not only provides a firm and secure anchor for the ground electrode but leaves the two electrodes in such relative positions that they may be easily adjusted for increasing or decreasing the length of the spark. If greater separation is required, a screw driver inserted 20 between the two points may be used to spread the points.

If it is desired to bring the two points closer together all that is required is to introduce a 25 screw driver between the electrode 17 and the shell wall and to thus force the electrode 17 toward the electrode 15.

The ring 16 also has a very definite function in the adjustment of the spark gap. In a very 30 hot motor the position of the gap should be in close proximity to the mouth of the spark plug. In a "cold" motor the gap should be in close proximity to the tip of the core 11. In case the motor pumps oil and fouls the spark plug, the 35 firing should take place as far as possible from the mouth of the spark plug so that the oil and carbon will be burned out as fast as it accumulates. The ring 16 makes such adjustment an easy matter. The spark plug is taken apart and 40 the electrode 17 is cut to the desired length after which the spark plug is again assembled. The ring 16 also facilitates and simplifies the stocking of the spark plugs by dealers. The ring 16 with 45 its ground terminal 17 may be carried in stock in various lengths of the terminals 17 so that the assembly may be made to suit the particular conditions for which the spark plug is to be used.

The ring 16 comprises a substantially cylindrical body 19 which has a diameter smaller than the interior diameter of the shell 10 below the shoulder 21 formed on the interior thereof so that the body 19 will not stick to the inside of the shell 10 after the spark plug has been in use 50 for a period of time. As shown in Fig. 1 there is a substantial space between the inside of the shell 10 and the exterior of the body 19 below the shoulder 21. The body 19 at its upper end is provided with a tapering flange 20 of substantially inverted frustro-conical configuration 55 which is adapted to rest upon the shoulder 21 which is of similar shape. By providing the

flange 20 and the shoulder 21 of tapering construction, when the bushing 12 is tightened to force the core 11 downwardly, the ring 16 will more readily seat on the shoulder 21 so that no gases will leak past the ring 16. Through the use 5 of a construction of this kind the spark plug can be marketed with a set of rings each having different length electrodes 17, so that the purchaser can determine exactly which type of electrode 17 to use, and if it is found desirable to change 10 electrodes after the plug has been in use for a period of time, a different type may be substituted, so that a single plug of this character will serve a three-fold purpose as shown in Figs. 2, 15 3 and 4.

Having thus described my invention in such full, clear, and exact terms that its construction and operation will be readily understood by others skilled in the art to which it pertains, what I claim as new and desire to secure by Letters 20 Patent of the United States is:

1. A spark plug comprising a member having a bore therethrough and a shoulder intermediate the ends of the bore, an insulated core within the bore and having its lower end disposed inwardly of the lower end of the member, a rib 25 on the core, a bushing threaded into the member to releasably hold the core in the member, an electrode axially of the core and terminating adjacent the lower end of the member, a ring 30 having a cylindrical peripheral surface loosely disposed in the bore and having a diameter less than the inner diameter of the bore below the shoulder whereby to provide a space between the ring and the interior of the member, a flange 35 carried by the ring engaging the shoulder, an electrode carried by the ring and extending downwardly and in the direction of the first electrode, and a gasket interposed between the flange and the rib. 40

2. A spark plug comprising a member having a bore therethrough and a tapering shoulder intermediate the ends of the bore, an insulated core within the bore and having its lower end disposed inwardly of the lower end of the member, a rib on the core, a bushing threaded into the member to releasably hold the core in the member, an electrode axially of the core and terminating adjacent the lower end of the member, a ring having a cylindrical peripheral surface loosely disposed in the bore and having a diameter less than the inner diameter of the bore below the shoulder whereby to provide a space between the ring and the interior of the member, an upwardly flaring flange carried by the 50 ring and engaging the shoulder to support the ring therefrom, an electrode carried by the ring and extending downwardly and in the direction of the first electrode, and a gasket interposed between the flange and the rib. 55 60
